DESIGN FOR A SUSPENDER BELT

Henry H. Thorne, Chicago, Ill.

Application July 29, 1943, Serial No. 110,794

Term of patent 14 years

To all whom it may concern:

Be it known that I, Henry H. Thorne, a citizen of the United States of America, residing at Chicago, county of Cook, and State of Illinois, have invented a new, original, and ornamental Design for a Suspender Belt, of which the following is a specification, reference being had to the accompanying drawing, forming a part thereof wherein:

I claim:

The ornamental design for a suspender belt, as shown.

HENRY H. THORNE.
